IRONING APPARATUS

Theodore R. Bush, Royal Oak, Mich., assignor to
 Borg-Warner Corporation, a corporation of
 Illinois

Application September 25, 1937, Serial No. 165,644

18 Claims. (Cl. 38—59)

This invention relates to roll ironers and has particular reference to improvements in power operated roll ironers, such as are adapted for domestic use.

As illustrated in the drawings, my invention is shown as being embodied in a portable roll ironer comprising a shoe element, a rotatable roll element cooperable with said shoe element for ironing purposes, said elements being mounted upon a common support and for movement relative to each other, and power transmission means, including a source of energy, operable for effecting relative movement between said shoe and roll elements and for rotating said roll element.

A principal object of the invention is to provide a new and improved form of ironing apparatus, suitable for domestic use.

Another object of my invention is to provide a new and improved form of roll ironer in which the ironing roll is mounted for movement toward and away from the ironing shoe.

Another object of my invention is to provide a new and improved form of transmission means for power operated roll ironers.

Another object of my invention is to provide a power transmission means for roll ironers which includes novel and improved mechanism for effecting relative movement between the roll and shoe elements and for driving the roll element when the same is in engagement with the shoe element.

Another object of my invention is to provide a transmission means for roll ironers, with an emergency release which effects movement of the roll element away from the shoe element, independently of the source of energy which normally operates the transmission means.

Another object of my invention is to provide a power transmission means for roll ironers which is simpler in construction, more compact in arrangement and which is adapted to provide automatic driving of the roll element when the same is brought into engagement with the shoe element; stopping of the roll element when the same is moved away from the shoe element; two speeds of rotation at which the roll element can be driven; movement of the roll element away from the shoe element independently of the source of power in the event of failure thereof; and, automatic resetting of the emergency release; and means to permit the roll and shoe elements to be operated for pressing purposes without rotation of the roll element.

For a better understanding of my invention reference may be had to the following specifica-

tion taken in conjunction with the accompanying drawings of which there are seven sheets and in which like characters are used to designate the same parts throughout the several views.

In the drawings:

Fig. 1 is a perspective view of a roll ironer embodying my invention;

Fig. 2 is a vertical sectional view through the ironing roll element and power transmission mechanism and taken generally in a plane along the line 2—2 of Fig. 1, looking in the direction of the arrows;

Fig. 2A is a vertical sectional view similar to Fig. 2 but on an enlarged scale showing the power transmission in greater detail;

Fig. 3 is an end view, with the end wall of the transmission housing and other parts partially broken away, illustrating in elevation certain parts of the transmission mechanism and of the support and mounting for the shoe element;

Fig. 4 is a vertical sectional view taken generally along the line 4—4 of Fig. 3, looking in the direction of the arrows and illustrating certain details of some of the controls for the transmission;

Fig. 5 is a horizontal sectional view through the transmission and taken generally along the staggered line 5—5 of Fig. 3, looking in the direction of the arrows;

Fig. 5A is a horizontal sectional view of a portion of the transmission showing a portion of the roll oscillating mechanism;

Fig. 6 is a vertical sectional view through the transmission, taken generally along the line 6—6 of Figs. 2 and 5, looking in the direction of the arrows, and illustrating the position of the mechanism when the roll is separated from the shoe;

Fig. 7 is a vertical sectional view through another part of the transmission, taken generally along the staggered line 7—7 of Fig. 2, and illustrating the position of the shifting mechanism when the roll is away from the shoe;

Fig. 8 is a vertical cross sectional view through the roll element and its supporting means and taken generally in a plane along the line 8—8 of Fig. 2, looking in the direction of the arrows;

Fig. 9 is a horizontal sectional view taken along the line 9—9 of Fig. 3, looking in the direction of the arrows and illustrating certain details of the knee-operated control of the transmission;

Fig. 10 is a front elevational view (the front wall of the transmission being broken away) of a modified form of control and emergency release for the transmission mechanism;

Fig. 11 is a vertical sectional view of the trans-

mission taken on a plane as indicated by the line 11—11 of Fig. 10;

Fig. 12 is a front elevational view of part of the transmission case and controls for the modification illustrated in Figs. 10 and 11;

Fig. 13 is a horizontal sectional view through a portion of a modified form of transmission;

Fig. 14 is a vertical sectional view through the transmission shown in Fig. 13; and,

Fig. 15 is a vertical sectional view taken substantially upon the plane indicated by the line 15—15 of Fig. 14.

Referring to Fig. 1, there is illustrated in perspective a roll ironer embodying my invention. This roll ironer, in the form in which it is illustrated, is especially adapted for domestic use and in general comprises legs 18 supporting a movable table 20 forming a portable support for a shoe element indicated generally at 22 and a roll element indicated generally at 24. The roll element 24 in general comprises a cylindrical padded roll supported from the housing of a transmission indicated generally at 26, the transmission being supported upon the top surface of the table 20 and at one end thereof.

The shoe element 22 may be of any conventional or preferred construction and includes a polished metallic face 28 (Fig. 3) cooperable with the outer surface of the roll 24 for ironing or pressing materials which are passed between the surface of the roll 24 and the face 28 of the shoe 22 when the same are in contact with each other. The shoe 22 may be provided with means for heating the same and may be supported by an arm 30 of a bell crank 32, which is pivoted upon a horizontal axis at 34 in brackets 35 secured to the underside of support 20. The bell crank 32 may be biased to the position illustrated in Fig. 3 by spring means 36 which forms a resilient stop for limiting clockwise movement of the bell crank about its pivot. The shoe 22 is adapted, when free of the roll element, to be supported approximately in the position illustrated in Fig. 3 and upon the upper end of the arm 30 in such a manner that the shoe 22 will have at least a limited universal movement with respect to the arm 30, so that the face 28 of the shoe may be properly presented to the surface of the roll element 24 or to any material arranged thereon for ironing. When the roll element is brought into cooperative relationship with the face 28 of the shoe element 22, the mounting therefor is adapted to permit the shoe element 22 to move in such a way that pressure is substantially uniformly distributed over the contacting surfaces of the shoe and roll elements and so as to permit the ironing apparatus to be used for ironing or pressing relatively thick or thin materials. The shoe element 22 is maintained in a centered position relative to arm 30 by means of a spring 37 extending between these two parts.

Referring now to Fig. 2, the roll 24, as illustrated, may comprise a tubular shell 38 of sheet metal, the outer cylindrical surface of which is continuously covered by padding 39 and a smooth cloth 40.

One end of the roll 24 may be provided internally thereof with a bearing 42 supported by an oscillatable journal 43, and the other end of the roll 24 may have a bearing provided by a bushing 44 carried by an end plate 45 which is secured to and closes one end of the shell 38. The bushing 44 is journaled upon a bearing surface 46 provided by one end of a tube 47. A washer 48 may be arranged between one end of

the bushing 44 and a snap ring 49 arranged in an external groove in the end of the tube 47 for securing the roll 24 against axial displacement from its supporting bearings 43 and 44. The end 5 of the tube 47 may be closed by a plug 50, having an ornamental circular cap 51 which covers the snap ring 49. The transmission end of the shell 38 may be closed in part by a crescent shaped plate 52 carried by a bracket 54. The bracket 54 is supported by a bearing plate 56 which is secured fast at 58 to the transmission end of the tube 47.

The tube 47 may be supported approximately intermediate the ends thereof by an arm or member 60 and which member 60 is illustrated as being provided with a pair of aligned bores 62 located in a bifurcation of said member through which the tube 47 extends and wherein said tube is clamped by means of a pair of set screws 64, 20 the ends of which may extend through suitable apertures in the tube 47 so that the same is securely locked against displacement.

The member 60 is provided with a cylindrical bearing surface 66 by means of which it is journaled for oscillation upon a bearing surface provided by one end of a rigid supporting tube 68, the other end of which tube may be press fitted within a socket 69 formed by a boss on the transmission casing and locked in such socket by 30 means of a set screw 70 (Fig. 5). The bearing plate 56 of the roll assembly is provided with an opening 72 through which the supporting tube 68 extends. The member 60 is further provided with a collar portion 74 to which there is secured by means of a key 76 and a locking screw 78, one end of an oscillating tube 80 which is arranged within and coaxially of the supporting tube 68. The oscillating tube 80 extends through the supporting tube 68 and into the housing of the transmission where it is connected to an oscillating mechanism, so that upon oscillation of the tube 80, the roll 24 will be shifted into and out of engagement with the ironing shoe 22.

A roll driving shaft 82 extends through the 45 oscillating tube 80 and is supported by means of a pair of bushings 84 arranged at opposite ends of the tube 80. The axis of the roll driving shaft 82 is arranged coaxially with the axis of the tubes 80 and 68 and within the roll the shaft 82 has 50 fixed thereto a pinion 86, the teeth of which mesh with the teeth of an internal gear 88 carried by the shell 38 of the roll 24. The gear 88 may be connected to the shell 38 of the roll 24 by means of a plurality of screws 90 and may, as illustrated, 55 have a hub and bearing 92 journaled on the tube 47 next to the member 60. The supporting tube 68, as illustrated, extends only to a point approximately midway the ends of the roll 24 and the member 60 supports the tube 47 approximately midway of the ends thereof.

The transmission 26 provides means for transmitting power from an electrically operated motor 100 to the roll 24 for rotating the same as well as for moving the roll into engagement with the shoe 22 so as to apply pressure to material placed upon the roll 24 for ironing or pressing. The transmission 26 includes a rigid housing 102, which includes a removable cover 104, and provides a means for housing and supporting the transmission mechanism and the motor 100 and for supporting the roll 24. The housing 102 is adapted to be rigidly secured to the frame of the support 20, such as by means of a plurality of bolts 106 which extend through suitable openings in the frame of the support

20 and engage threaded portions 108 (Fig. 2A) of the housing 102 thereby forming a rigid, but detachable connection between the housing 102 and the support 20.

The motor 100 is suspended by means of four posts 110 from a horizontally arranged wall portion 112 of the housing 102. The wall portion 112 is provided with a central opening through which the shaft 114 of the motor extends and is connected by means of a flexible coupling 116 to a worm shaft 118, which shaft is journaled at its lower end in a bushing 120 and at its upper end in a bushing 122 (Fig. 6). The bushing 120 may be press fitted within a bore 124 formed in a partition 125 which closes the bottom of the compartment within which the transmission mechanism is arranged. A nut 126, held in place by means of a locking plate 128, is threadedly secured to the lower portion of the bore 124 and provides a seat upon which a shoulder 130 of the shaft 118 is located. The bushing 122 is press fitted within a socket 132 formed in the upper part of the transmission housing and a thrust plate 134 is arranged in the top of said socket 132. Between the underside of the thrust plate 134 and the end of the worm shaft 118 a ball bearing 136 may be arranged. A grease cup 138 may be carried by a projecting part of the bushing 122. The worm shaft 118 is provided with a worm 140, the teeth of which mesh with the teeth of a worm wheel 142.

The transmission mechanism (Fig. 2A) includes a roll shifting or oscillating clutch indicated generally at 144, a roll driving clutch indicated generally at 146, an emergency release clutch indicated generally at 148, and a two-speed clutch indicated generally at 150. The roll shifting or oscillating clutch 144 controls the movement of the roll 24 toward and away from the shoe 22 during normal operation 40 of the ironing machine. The roll driving clutch 146 controls the rotation of the roll so that the roll 24 may be rotated when the same is in engagement with the shoe 22, and so that the rotation of the roll will be stopped when the same is separated from the shoe 22. The emergency release clutch 148 permits the roll 24 to be shifted away from the shoe 22 independently of the source of power and in the event of failure thereof. This clutch 148 is for emergency use to permit the roll 24 to be moved away from the heated shoe 22 to eliminate the possibility of burning the padding of the roll 24 if the supply of current to the motor 100 fails. The two-speed clutch 150 is adapted to connect the roll 24 to its driving mechanism so that the roll can be driven at either of two speeds, or to disconnect the roll from its driving mechanism so that the roll will not rotate when the same is brought into engagement with the shoe 22. When it is desired to use the ironer for pressing purposes, rotation of the roll may not be desired, hence, the clutch 150 may be set so as to disconnect the roll from its driving mechanism.

The worm wheel 142 is mounted for rotation upon a shaft 152, and which shaft is held at one end in a bore 154 (Figs. 2 and 2A) in the transmission case by a set screw 156, the other end of the shaft 152 being rigidly supported by a bearing plate 158 which forms a removable closure for the open end of the compartment in which the transmission mechanism is disposed. The plate 158 may be secured to the

walls of the transmission housing 102 by means of a plurality of bolts 160 (Fig. 5).

As previously explained, the worm wheel 142 is rotatably supported upon the shaft 152 and includes a sleeve portion or clutch member 162 (Figs. 2 and 2A) extending axially from the hub of the worm wheel 142, and the outer surface of which sleeve portion 162 is cylindrical and forms a clutching surface of the spring clutch 144, which is the roll shifting or oscillating clutch. Said clutch 144 further includes a cylindrical drum portion or clutch member 164, a clutch spring 166 and a clutch plate 168 provided with a pair of laterally extending lugs or stops 170 (Fig. 6), circumferentially spaced on the circular plate 168, 180° apart. The clutch spring 166 is coiled and may have an internal diameter slightly in excess of the external diameter of the cylindrical surfaces provided by the clutch members 162 and 164. The external diameter of the clutch members 162 and 164 should be the same, and the clutching surface should be smooth and continuous so as to provide a good clutching surface. One end 172 (Fig. 7) of the clutch spring 166 extends radially and is located between a pair of axially extending pins 174 carried by an eccentric 176 and the other end 178 of the clutch spring is located in a notch provided in a laterally extending lug formed on the clutch spring side of the clutch plate 168. The clutch plate 168 is carried by the clutch member 162 and the side of the clutch plate 168 is held by the spring 166 in frictional engagement with a flat side of the hub of the worm wheel 142. Looking at Fig. 6, the worm wheel will rotate in a counter clockwise direction. The clutch plate 168 is kept from rotating with the worm wheel 142 by means of a finger 182 having an abutment 184 which normally is adapted to rest in the path of rotation of the lugs 170. Movement of the finger 182 which is pivoted at 186 to the position shown in dotted lines in Fig. 7 will move the abutment 184 out of the path of the lugs 170. Rotation 50 of the worm wheel 142, when the motor is operating, and if the abutment 184 is moved out of the path of travel of the lugs 170, will permit the clutch plate 168 to be rotated due to the frictional drag between the clutch plate 168 and the side of the hub of the wheel 142. So soon as the clutch plate 168 begins to rotate, and assuming the eccentric 176 to be at rest, the clutch spring 166 will begin to wind up upon the clutching surface of the members 164 and 162 as the result of which the inside diameter of the clutch spring 166 will contract and frictionally grip the external cylindrical surface of the clutch members 162 and 164. The clutch member 162 rotates with the worm wheel 142, and the clutch member 164 will be rotated with the clutch member 162 so soon as the clutch spring 166 operates frictionally to grip the clutching surface of the members 162 and 164, the end 172 of the clutch spring being anchored to the eccentric 176 which is connected to the clutch member 164. If the abutment 184 immediately after being moved out of the path of travel of the lugs 170 is permitted to return (in a manner hereinafter described) to the position in full lines in Fig. 7, the second lug 170 upon 60 the clutch plate 168 will be engaged by the abutment 184 as soon as the clutch plate 168 has travelled through 180° of movement and such engagement of the second lug 170 with the abutment 184 will stop the rotation of the clutch 65 70 75

plate 168 and operate to break the driving connection between the clutch spring 166 and the clutching surface of the clutch member 162, inasmuch as the end 178 of the clutch spring is connected to the clutch plate 168. It will thus be seen that the clutch 144 when engaged will remain so for 180° of rotation, that is, the clutch will remain engaged until the driven member 164 thereof has been rotated through 180° of movement by the driving member 162 of the clutch.

The finger 182 forms a part of a lever which is pivoted by a pin 186 to a lug 185 formed on the inside of the transmission housing. The finger 182 is adapted to be moved out of the position illustrated in full lines in Figs. 6 or 7 by means of a pin 187 mounted for vertical movement in a guide 188 formed in the wall of the transmission housing, the pin 187 being provided externally of the transmission housing with a push button 190 and, internally of the transmission, being adapted to engage a laterally extending pin 192 carried by a part of the finger 182 which is below the pivot point 186. The finger 182 extends downwardly to a point where it is engaged by an arm 194 (Fig. 3) mounted upon the upper end of a vertically arranged crank arm 196 so that movement of the arm 194 in a clockwise direction (looking at Fig. 5) will displace the lower end of the finger 182 to lift the abutment 184 out of the path of the projecting lugs 170 on the clutch plate 168. The push button 190 is adapted to actuate the finger 182 to remove the abutment 184 from the path of the lugs 170 of the clutch plate 168, upon being pushed downwardly and released. A spring 198 (Fig. 7), one end of which is connected to the finger 182 on the abutment side of the pivot 186 is adapted for returning the abutment 184 to its normal position in the path of the lugs 170. The arm 194 is adapted to act as a return stop for the finger 182. The crank arm 196 (Fig. 5) is mounted in a guide 198 and the lower end of the crank arm has an arm 200 (Fig. 9) which engages in a slot 202 in a bell crank 204 mounted on a vertical pivot 206. A link 208 connects one arm of the bell crank 204 to one end of a lever 210 pivoted at 212. The other end of the lever 210 has connected to it one end of an axially slidable rod 213 mounted for movement in guides 214 and having at one end thereof a depending pad 215 which extends below the support 20 and is adapted to be engaged by the knee of an operator of the ironing machine. The connection between the slidable rod 213 and the arm 200 is such that the arm 194 will be moved in a clockwise direction about its pivot upon movement of the knee pad 215 in either direction. The push button 190 provides a fingertip control for the roll oscillating clutch 144 while the pad 215 provides a knee control for the power clutch so that the clutch may be operated in two different ways, whichever is most convenient. In either case, the member 190 or 215 is displaced slightly and then immediately released and in either such event, the clutch 144 will engage to transmit 180° of movement to the driven member 164 of the clutch.

The eccentric 176 is adapted to shift the roll 24 into engagement with the ironing shoe and is moved through 180° of travel every time the clutch 144 is engaged. The eccentric 176 is provided with a circular peripheral surface 220 which is fitted within an encircling strap portion 222 of a connecting link 224 (Fig. 7). The end of the link 224 is pivotally connected to a pin 226 carried by an arm 228 of a sleeve 230 (Figs. 2

and 2A) through which one end of the oscillating tube 80 extends. The inside of the sleeve 230 forms a bearing for one end of the tube 80 and the outside of a part of the sleeve is supported by a bushing 232 press fitted into one end of the roll supporting tube 66. The sleeve 230 is formed to provide the driving part 234 of the spring or emergency release clutch 148. Said emergency release clutch 148 further includes a driven part 236 keyed for rotation with the oscillating shaft 80 by a key 238 and a clutch spring 240 one end 242 (Fig. 7) of which is looped around an anchor pin 244 carried by a radially extending portion of the sleeve 230, and the other end 246 of which is bent outwardly and away from the main body of the spring so as to be engageable by a clutch releasing member 248. The clutch parts 236 and 238 are provided with aligned cylindrical clutching surfaces, and the clutch spring 240, when coiled, preferably has an inside diameter substantially the same as the outside diameter of the clutching surfaces of the clutch parts 234 and 236. The spring clutch 148 is one form of a self-energizing clutch which operates to transmit torque in one direction and which is adapted to permit over running of the clutch parts when the speed of the driven part thereof exceeds that of the driving part. In the present instance the clutch 148 is adapted to transmit rotary motion from the part 234 to the part 236 upon clockwise movement of the driving part 234 (looking at Fig. 7). As the driving part 234 of the clutch 148 forms a part of the sleeve 230 connected by the arm 228 to the connecting rod 224, it is apparent that upon shifting of the eccentric 180° from the position in which it is illustrated in Fig. 7, the clutch 148 will operate to oscillate the tube 80 so as to bring the ironing roll 24 into ironing relationship with the face of the ironing shoe 22.

Due to the nature of the spring clutch 148, it is apparent that when the eccentric 176, connecting rod 224, and sleeve 230 are in the position illustrated in Fig. 7, the clutch spring 240 will not grip the driven clutch part 236 and return it to the position illustrated in Fig. 7 as the clutch spring 148 will only operate to transmit torque when the sleeve 230 moves in a clockwise direction.

The oscillating tube 80 is provided with a stop lever 252 (Fig. 6) which has a hub 254 fitting over the end of the tube 80 and rigidly secured thereto by means of a set screw 256 (Figs. 2 and 2A). The end of the stop lever is adapted to engage a shaft 258 (Fig. 6) so as to limit the movement of the ironing roll 24 away from the ironing shoe 22. The stop lever 252 also carries a pin 260 which is adapted to extend behind the pin 244 (as shown in Fig. 6) so as to prevent the displacement of the roll toward the shoe when the roll is away from the shoe and the shifting mechanism is arranged in the position illustrated in Figs. 6 and 7. The oscillating tube stop lever 252 also is provided with a catch 262 to which one end of a spring 264 is hooked, the other end of the spring being hooked to a lug 266 of a bell crank 268 pivotally secured at 270 by a pin to a part 272 formed integrally with the encircling strap portion 222 of the connecting rod 224. When the clutch 144 is operated so as to permit the shifting mechanism of the transmission to shift to the position illustrated in Fig. 7, the spring 264 will operate to shift the ironing roll 24 away from the ironing shoe 22.

It will thus be seen that the power of the

motor is utilized for shifting the ironing roll 24 into engagement with the ironing shoe 22, whereas the spring 284 is utilized for shifting the ironing roll 24 away from the ironing shoe 22. However, the spring 284 cannot shift the ironing roll 24 away from the ironing shoe 22 unless the clutch 144 is actuated or unless the emergency release clutch 148 is released, as will hereinafter be described. The bell crank 268 (Fig. 7) includes an arm 273 which constitutes a brake member and which is cooperable with a braking surface 274 formed by a peripheral segment of the eccentric 176. The brake members 272 and 274 are adapted to cooperate only when the shifting mechanism is shifting from roll-engaging position to the position illustrated in Fig. 7, it being observed that the periphery of the eccentric is relieved at 275 (Fig. 7) so that when the ironing roll 24 is being shifted into engagement with the ironing shoe, no braking effect is obtained.

The shaft 258 (Fig. 5) at one end is supported in a boss 280 formed on the inside of the wall of the transmission case 102 and at the other end is supported by the bearing plate 158. A manually operable control member 282 (Figs. 3 and 7) for the emergency release clutch 148 is carried externally of the transmission case upon a shaft 284 rotatably supported in a bore formed in the wall of the transmission case, and the shaft 284 inside of the transmission case is provided with a pair of arms 285 (Fig. 4) each of which is arranged above a lug 286 carried by a sleeve 287 which also carries the emergency clutch release member 248 (Fig. 7). Rocking of the shaft 284 in either direction by manipulation of the control member 282 will cause one of the arms 285 to move downwardly and engage one of the lugs 286 as a result of which the emergency release clutch member 248 will move in a counter-clockwise direction looking at Fig. 7. Such movement of the emergency clutch release member 248 will engage the end 246 of the clutch spring of the emergency release clutch and will uncouple the clutch member 286 from the grip of the clutch spring, thereby permitting the spring 284 to shift the ironing roll 24 away from the ironing shoe. The control member 282 is provided so that in the event of failure of the source of power for the motor 100, the ironing roll 24 can be moved quickly away from the ironing shoe 22.

After the emergency release clutch 148 has been disengaged to permit the separation of the ironing roll and shoe, it is necessary to operate the finger tip control 190 twice in order to shift the ironing roll 24 back into engagement with the ironing shoe, after the source of power for the motor 100 has been restored. The spring 198 at one end thereof is secured to a part of the emergency release clutch member and at the other end thereof is secured to a part of the finger 182 of the roll oscillating clutch release. The spring 198 thus serves to maintain in their normal positions the clutch release members 182 and 248.

The roll driving clutch 146 (Fig. 2) which is operable for connecting the roll to the motor so as to drive the roll when the same is in engagement with the ironing shoe, and to disconnect the roll from the motor when the roll is separated from the shoe, comprises a dog clutch formed by a pair of complementary jaw clutch members 290 and 292. The jaw clutch member 290 may be formed integrally with the hub of the worm wheel 142 so as to be continuously driven when the

motor is operating. The jaw clutch member 292 is formed on one end of the hub 294 slidably and rotatably mounted upon the shaft 152. Hub 294 is formed to include a pair of gears 296 and 298 having different pitch diameters. The gear 296 is in constant mesh with a gear 300 rotatably mounted upon the roll driving shaft 82 and arranged adjacent the oscillating tube stop lever hub 254. The gear 298 is in constant mesh with a gear 302 also rotatably arranged upon the roll driving shaft 82. The two-speed clutch 150 is adapted for selectively connecting the gears 300 and 302 to the roll driving shaft 82 for operating the same. The two-speed clutch 150 is manually operated as will hereinafter be explained.

The roll driving clutch 146 is adapted to be engaged and disengaged in accordance with the movement of the ironing roll 24 toward and away from the ironing shoe 22. A shift fork 304 (Figs. 3 and 5) carried by a hub 306 fast upon a slidable shaft 308 is adapted for engaging and disengaging the roll driving clutch 146. The shaft 308 is mounted for sliding movement in a pair of guides 310 carried by the wall of the transmission and is biased into clutch engaging position by a spring 312 (Fig. 5) arranged about the shaft 308 and confined between the hub 306 and the bearing plate 158 of the transmission case. In the position in which the shift fork 304 is illustrated in Fig. 5, the roll driving clutch 146 is disengaged. The engagement and disengagement of the clutch 146 is controlled by an eccentric 314 formed integrally with the roll-oscillating, stop lever 252. The eccentric 314 includes a relieved portion 316 which, when brought into line with the end of shaft 308, will permit the spring 312 to shift the fork 304 and clutch member 294 so as to engage the clutch 146. In the position in which the parts are illustrated in Fig. 6, the eccentric 314 is holding the clutch 146 disengaged and the ironing roll 24 is separated from the ironing shoe 22. When the eccentric 176 has shifted the roll into engagement with the shoe, the relieved portion 316 of the eccentric 314 will be in line with the end of the shaft 308. The roll driving clutch 146, it will be seen, thus is engaged and disengaged in accordance with the shifting of the roll toward and away from the shoe, and this will be so whether the roll is shifted away from the shoe as a result of operation of the fingertip control 190 or the operation of the emergency release control member 282.

The two-speed clutch 150 includes a pair of oppositely arranged spring clutches indicated generally at 320. The hub of each of the gears 300 and 302 is formed to provide a cylindrical clutch part 322 and a clutch member 324, common to both of the clutches 320 and fast on the roll driving shaft 82 is adapted to provide a cylindrical clutching surface at each end thereof and next to the cylindrical clutching surfaces of the clutch parts 322. Each of the clutches 320 includes a clutch spring 326 coiled about the adjacent clutch surfaces of the parts 322 and 324 and which are adapted to transmit torque from the members 322 to the member 324 for driving the roll driving shaft 82. A shiftable clutch member 327 is slidably splined upon a splined portion of the clutch member 324 and is provided with a series of axially extending pins 328. When the clutch member 327 is shifted either to the right or to the left of the position in which it is illustrated in Figs. 2 and 5, one of the pins 328 will engage with one of the ends 330 of one of the clutch springs 326. The clutch

springs 326 will rotate with the gears 300 and 302, one at a faster rate than the other, and when the clutch member 327 is shifted, for example to the left, one of the pins 328 thereof will engage the end 330 of the left hand clutch spring 326 as a result of which the end of the clutch spring 326 will contract and grip the clutching surface of the clutch member 324 as a result of which torque will be transmitted from the gear 300 through the left hand clutch spring 326 and clutch member 324 to the roll driving shaft 82. During such time as one of the clutches 320 is operating, the other of the spring clutches will be inoperative and the clutch spring 326 thereof will simply overrun the contiguous portion of the clutch member 324. The operation of the spring clutches 320, 148, and 144 is substantially the same except that in the cases of the spring clutches 144 and 148, the clutches are self-energizing and are normally set up in such a way as to transmit torque, whereas the clutches 320 need to be engaged or acted upon in order to transmit torque.

The shiftable member 327 (Fig. 5) of the clutch 150 is manually operable by a shift fork 332 slidably upon the shift rod 258. A control member 334 (Fig. 3), similar to the control member 282, is mounted externally of the transmission case upon a shaft 336, (Fig. 4) and, internally of the transmission case, shaft 336 is provided with a fork 338. The shift fork 332 includes a sleeve 333 free on the shaft 258 and which sleeve is provided with a pin 337 which is engaged by a fork 338 so that upon actuation of the control member 334, the clutch member 327 may be shifted either to the right or to the left for selectively connecting either of the gears 300 or 302 to the shaft 82 for driving the same.

The end of the shaft 82 is provided with a cap 340 which is secured thereto by means of a screw 342 and prevented from rotating relative thereto by a pin 344. A bushing 346 is pressed into an aperture in plate 158 and forms a bearing in which cap 340 is rotatable thus supporting the right end of shaft 82 as viewed in Fig. 2A.

In the modification of the invention shown in Figs. 10 to 12, the roll oscillating clutch and the emergency release clutch actuating members are combined thus reducing the number of control buttons provided exteriorly of the transmission.

The mechanism of the transmission remains substantially unchanged, the clutch plate 168 being provided, as in the disclosure of Figs. 1 to 9, with a pair of laterally extending lugs or stops 170, circumferentially spaced on the circular plate, 180° apart. A stop 360 carried on the end of an arm 362 of a bell crank lever is adapted to engage stops 170 to operate the roll oscillating clutch in the manner described in connection with Figs. 1 to 9.

The bell crank lever is mounted for oscillation upon shaft 258 and has a second arm 364 laterally offset with respect to arm 362 for engaging the curled end 246 of the clutch spring 240. A third arm 366 of the bell crank projects toward the front of the casing 102 for the transmission mechanism, and is adapted to be engaged for downward movement by a lug 368 on a lever 370 secured to a shaft 372 which projects through casing 102 and is adapted to be rotated by a control member 374 secured exteriorly of the casing to the shaft 372. A coil spring 376 secured between the casing 102 and an arm 378 of the bell crank lever tends to rotate the bell crank lever

in a clockwise direction thus maintaining the bell crank lever in operative relation with respect to clutch plate 168 of the roll oscillating clutch and out of disengaging position with respect to the curled end 246 of the clutch spring 240.

An additional bell crank member 378 projects downwardly into engagement with the lever 364 secured to the upper end of shaft 196 of the knee operated linkage shown in Fig. 9.

It will be noted that a slight amount of clearance is provided between the curled end 246 of the clutch spring 240 and the lever 364 of the bell crank. It will thus be recognized that the member 360 may be moved out of engagement with the stops 170 without releasing the clutch spring 240. It will be recognized that the construction of Figs. 10 to 12 materially reduces the number of controls with which the operator is required to deal thus simplifying the operation of the machine. It will also be appreciated that the release of the clutch spring 240 in case of emergency will be accompanied by release of the clutch member 168. The roll oscillating clutch will thus be seen to be in position for the next cycle of the machine even though the emergency release clutch has been actuated. A pin 375 upon the lever 370 constitutes a stop which has engagement with the shaft 258 to prevent lever 370 from being rotated past a horizontal position in a clockwise direction.

In the modified form of transmission shown in Figs. 13 to 15 the main elements thereof remain the same. The transmission is again housed in a casing 102 and is again provided with a roll oscillating clutch 144 which is of the spring type. The only difference in this transmission lies in its use of a dog clutch 148' in place of the spring clutch 148 employed in Figs. 1 through 12. With such a construction the roll is adapted to be moved during normal operation both into and out of operative relation to the shoe, the dog clutch 148' being constantly in engagement.

The dog clutch 148' will be seen to comprise a collar member 400 splined at 402 to the roll oscillating tube 80 and having teeth 404 for engagement with corresponding teeth upon a collar 406 which corresponds to the collar 234 shown in Fig. 2A and is adapted to be driven by the roll oscillating clutch 144 through the eccentric 220 and connecting rod 222. The clutch collar 400 is normally maintained in its shifting position to the left by means of a spring 408 encircling the roll oscillating tube 80 and bearing against the collar 400 and the flange end 410 of a sleeve 412 which is held against endwise displacement by a collar 414 pinned at 416 to the roll driving shaft 82.

During normal operation of the ironing machine the clutch 148' will remain in engagement to transmit power from the eccentric 220 in both directions. During emergencies however when the power may fail, it is necessary to shift the roll out of engagement with the shoe to prevent injury to the clothing which may lie between these two elements. To this end the shiftable collar 400 is provided with a slot 418 with which a shift fork 420 is engaged. The shift fork is slidably disposed upon a shaft 258 for movement along the axis thereof. A handle 422 is provided upon the exterior of the casing 102 and is fixedly secured to a shaft 424 extending through the casing. The portion of the shaft 424 within the casing is provided with an offset portion 426 which carries a pin 428 engaging with a laterally

extending portion 430 of the shift fork 420. Movement of the handle 422 in a counterclockwise direction when viewed from the front results in movement of the shift fork 420 to the right as viewed in Fig. 13. This will result in the 5 clutching collar 400 being moved to the right, out of engagement with the collar 406 against the action of the spring 408. The shaft 424 engages a laterally extending slot in the portion 430 of the shift fork 420 to preserve the 10 alignment of the two parts.

The clutching collar 400 is provided with an extension 432 apertured at 434 to receive a spring 436 which is connected to an offset portion of the eccentric in the same manner as the 15 modification shown in Figs. 1 to 12 and particularly as shown in Fig. 7. Upon release of the clutch 148' the spring 436 becomes effective to rotate the collar 400 in a counter clockwise direction as viewed in Fig. 15 to rotate the roll oscillating tube 80 and move the roll away from the shoe.

The collar 400 is also provided with a second projection 438 which has a flat spot 440 for engagement with a pin 442. The pin is normally 25 pressed upwardly by means of a spring 444 wrapped around the pin and extending between a stationary portion of the casing 102 and a washer 446 pinned at 448 against upward movement with respect to the pin 442. Portion 440 30 of the arm 438 and the spring pressed pin 442 serve as a resilient stop means for arresting the oscillation of the roll away from the shoe under the influence of spring 436.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. In an ironing machine, a roll, a shoe, a source of power, a one-half revolution clutch driven from said source of power, a two-speed selective clutch driven from said source of power, a power transmitting connection between said one-half revolution clutch and the interior of the roll for moving the roll bodily against or away from the shoe, and a second power transmitting connection between said two-speed clutch and the interior of the roll for rotating the roll upon its axis, said power transmitting connections extending at least in part along a common axis to cause the connections to be operative in all positions of movement of the roll toward and away from the shoe.

2. In an ironing machine, a shoe, a roll mounted for bodily movement into and out of engagement with said shoe, a source of power, and a transmission mechanism, said transmission mechanism including a power driven clutch for bodily moving said roll, a clutch through which the roll is rotated about its axis, and instrumentalities dependent upon the position of the roll for connecting and disconnecting the roll rotating clutch said clutches having a part in common and being located upon a common axis to be driven from the source of power.

3. In an ironing machine, a shoe, a roll mounted for bodily movement into and out of engagement with said shoe, and a power transmission, said transmission including a roll moving clutch controlled by the operator, a roll 75

rotating clutch controlled by operation of the roll moving clutch, a manually controlled change speed clutch driven from the roll rotating clutch, and a manually disconnectible clutch driven from the roll moving clutch and permitting movement of the roll away from the shoe in the event of power failure.

4. A power transmission device comprising a pair of members mounted for rotation upon a common shaft and driven at different speeds from the same source of power, said members having hubs of equal diameter, a coiled spring carried by each of said members upon their facing sides and coiled about but frictionally free of their respective hubs, and a shiftable clutch member splined to a hub of the same diameter as the hubs on said members and loosely encircled by said springs, said clutch member being tightened on the hub between the springs and said shiftable clutch member having means engageable with either of the free ends of said springs thereby operatively to connect either of said pair of members to said shaft by contracting one of the springs into engagement with mating hubs.

5. In an ironing machine, a shoe, a roll, power operated means including a clutch for shifting the roll into contact with or away from the shoe, a stop for arresting movement of said clutch and said means every half revolution with the roll in engagement with or away from the shoe, a second clutch for permitting the roll to be shifted independently of the first clutch, and means for releasing said second clutch in the event of power failure comprising a lug carried by said stop.

6. In an ironing machine, a shoe, a roll, power operated means including a clutch for shifting the roll into contact with or away from the shoe, 40 a stop for arresting movement of said clutch and said means every half revolution with the roll in contact with or spaced from the shoe, a second clutch for permitting the roll to be shifted independently of the first clutch, and means for releasing said second clutch in the event of power failure comprising a lug carried by a manually movable member.

7. In an ironing machine, a shoe, a roll, power operated means including a clutch for shifting the roll into contact with or away from the shoe, 50 a stop for arresting movement of the clutch every half revolution with the roll in contact with or spaced from the shoe, a second clutch for permitting the roll to be shifted independently of the first clutch, means for releasing said second clutch in the event of power failure comprising a lug carried by a manually movable member, and single spring means for urging both the lug and the stop into operative position.

8. In an ironing machine, a resiliently mounted shoe, a roll mounted for bodily movement into and out of engagement with said shoe and rotatable about its axis, and a transmission for imparting the bodily and rotary movements to said roll, said transmission including a one-half revolution clutch for bodily moving the roll to stop the roll at the limits of its movement into and out of engagement with said shoe, a clutch for transmitting rotary movement to the roll and engaged by movement of the first clutch, and a speed selective device located in the train of rotary motion transmitting mechanism for varying the speed of rotation of the roll toward and away from the shoe.

9. Ironing apparatus comprising a shoe, a roll,

a source of power, a driving connection between said source of power and said roll for moving the roll into engagement with and away from the shoe, a clutch in said driving connection and operable for controlling the movement of said roll into engagement with and away from said shoe, and means, including a second clutch, arranged in said driving connection between said first clutch and said roll and manually disconnectible to permit said roll to be moved away from said shoe in the event of power failure.

10. Ironing apparatus comprising a shoe, a roll, a source of power, a driving connection between said source of power and said roll and operable for shifting said roll into engagement with said shoe, a clutch for controlling said driving connection, a second source of power, a driving connection between said second source of power and said roll for moving said roll away from said shoe, a clutch in said last mentioned driving connection and means for operating said clutches so as to control the movement of said roll toward and away from said shoe.

11. Ironing apparatus comprising a shoe, a roll shifttable into engagement with and away from the shoe, means for shifting the roll including a source of power, a roll shifting mechanism, a clutch between said source of power and said shifting mechanism, roll supporting mechanism, a clutch between said shifting mechanism and said supporting mechanism, means for controlling said first-mentioned clutch so as to control the power shifting of the roll into engagement with and away from the shoe, and means for operating said second-mentioned clutch for disconnecting the roll support from the source of power to permit movement of the roll away from the shoe independently of operation of the first-mentioned clutch in the event of failure of power.

12. Ironing apparatus comprising a roll element, a shoe element, one of said elements being mounted for movement toward and away from the other of said elements, a source of power, a driving member in constant connection with the source of power, a shifting member connected to said movable one of said elements, a driving connection including a pair of clutches between said driving member and said shifting member, one of said clutches constituting a shifting clutch and the other of said clutches constituting an emergency release clutch, said shifting clutch being arranged between said emergency release clutch and said driving member, said shifting clutch being engageable to complete the driving connection between said driving member and said shifting member so as to operate said shifting member for moving said shoe and roll elements into and out of engagement, spring means connected to said shifting member and adapted for operating the same to effect a separation of the said roll and shoe elements, said emergency release clutch being adapted to break the driving connection between said shifting clutch and said shifting member to permit said spring means to effect a separation of said ironing elements in the event of power failure.

13. Ironing apparatus comprising a roll element, a shoe element, one of said elements being mounted for movement toward and away from the other of said elements, a source of power, a driving member in constant connection with said source of power, a shifting member con-

nected to said movable one of said elements, a driving connection including a pair of clutches between said driving member and said shifting member, one of said clutches constituting a shifting clutch and the other of said clutches constituting an emergency release clutch, said shifting clutch being arranged between said emergency release clutch and said driving member, said shifting clutch being engageable to complete the driving connection between said driving member and said shifting member so as to operate said shifting member for bringing said shoe and roll elements into engagement, spring means connected to said shifting member and adapted for operating the same to effect a separation of the said roll and shoe elements, said emergency release clutch being adapted to break the driving connection between said shifting clutch and said shifting member to permit said spring means to effect a separation of said ironing elements in the event of power failure, a driving connection between said driving member and said roll element for driving the same, a roll driving clutch in said driving connection and means carried by said shifting member and operable for engaging and disengaging said roll driving clutch.

14. Ironing apparatus comprising a roll, a shoe, said roll being mounted for movement toward and away from the shoe, means including a source of power operable for shifting said roll into engagement with and away from the shoe, a manually operable clutch for controlling said shifting means, a driving connection between said source of power and said roll element, means operable in response to shifting of said roll for controlling said last-mentioned clutch so that the roll element will be driven when said roll and shoe are in engagement with each other and so that rotation of said roll will cease when said roll and shoe are separated and an emergency release mechanism arranged to control said shifting means so as to effect movement of said roll away from said shoe and disengagement of said second-mentioned clutch upon failure of power.

15. Ironing apparatus comprising a roll, a shoe, said roll being mounted for movement toward and away from the shoe, a source of power, a driving connection between said source of power and said roll and operable for effecting movement of said roll toward the shoe, a pair of clutches arranged in series in said driving connection, a driving connection between said source of power and said roll for rotating the same, means for shifting said roll away from the shoe, said last-mentioned means being operable in response to operation of either of said clutches, said driving connection for moving said roll into engagement with the shoe being operable only in response to operation of one of said clutches, a clutch in said roll driving connection, means operable in response to shifting of said roll for operating said roll driving clutch so that the roll will be driven when said roll and shoe are in engagement with each other and so that the rotation of said roll will stop when separation of said roll and shoe is effected, and means for operating said first two mentioned clutches, one of said two clutches being normally employed for shifting the roll under power and the other being employed in the event of power failure in order to retract the roll from engagement with the shoe.

16. Ironing apparatus comprising a roll, a

shoe, said roll being mounted for movement toward and away from the shoe, a source of power, a clutch, a driving member driving said clutch from said source of power, a driving connection between said driving member and said roll for effecting shifting thereof into engagement with the shoe, a one-way clutch arranged in said driving connection between said first-mentioned clutch and said roll, means, directly connected to a part which moves with said roll, for effecting movement thereof away from the shoe in the event of power failure, a roll driving element, a driving connection between said driving member and said roll driving element, a clutch in said roll driving connection, and means responsive to movement of said roll for operating said clutch in said roll driving connection so that said roll is driven when the roll and shoe are in engagement and is stopped when said roll and shoe are separated.

17. In an ironing machine, a shoe, a roll movable into and out of engagement with said shoe, power means including a member for moving

5 said roll into engagement with said shoe, spring means for moving said roll out of engagement with said shoe, and a brake engageable with said member for retarding the movement of the roll away from the shoe under the action of said spring means, said roll moving spring means being connected at one end to said brake to apply the same against said member.

10 18. In an ironing machine, a shoe, a roll movable into and out of engagement with said shoe, power means including a member for moving said roll into engagement with said shoe, spring means for moving said roll out of engagement with said shoe, and a brake engageable with said member for retarding the movement of the roll away from the shoe, said roll moving spring being connected at one end to said brake to apply the same against said member, and said member being relieved along a portion of its brake-presented surface to prevent contact between the brake and member during movement of the roll toward the shoe.

20 THEODORE R. BUSH.
